DESIGN FOR A BRUSH

Felix R. Rapids, Chicago, Ill.

Application August 23, 1937, Serial No. 71,257

Term of patent 7 years

To all whom it may concern:

Be it known that I, Felix R. Rapids, a citizen of the United States and a resident of the city of Chicago, in the county of Cook and State of Illinois, have invented a new, original, and ornamental Design for a Brush, of which the following is a specification, reference being had to the accompanying drawing, forming a part thereof.

On the drawing:

The figure is a perspective view of a brush, showing my new design.

The dominant features of my design reside in the portions shown in full lines.

I claim:

The ornamental design for a brush as shown and described.

FELIX R. RAPIDS.
